UNITED STATES PATENT OFFICE.

GEORGE W. STOUT, OF MERCHANTVILLE, NEW JERSEY.

PACKAGE TIE.

Application filed April 18, 1922. Serial No. 555,107.

To all whom it may concern:

Be it known that I, GEORGE W. STOUT, a citizen of the United States, residing at Merchantville, in the county of Camden, State of New Jersey, have invented a new and useful Package Tie, of which the following is a specification.

My invention relates to package ties, and comprises a novel construction of a body portion having a nearly closed eye therein located on about the median line of the body and internal recesses of a novel construction collocated with a side recess, said eye being provided with a tying cord of such dimensions in cross-section as to completely fill said eye, so that it cannot be laterally pulled therefrom, the ends of said tying cord being each provided with a head of cement or the like of such area that the tying cord cannot be drawn through said eye at either end thereof, whereby a concrete unitary structure is produced, comprising the tie body and the cord provided with the cemented ends or heads, which cannot be disconnected therefrom.

By my novel construction, a novel, concrete, unitary structure is provided wherein the cord and tie are inseparable and which can be reused almost indefinitely, since after one end of the cord begins to show any indication of appreciable wear from the effects of the repeated tying operations, it is only necessary to sever the knot above the plate and pull the cord through the body of the plate which reverses the cord, thereby positioning the worn portion of the cord, so there will be no wear from the tying operation placed upon it, thereby practically redoubling the life of the device.

To the above ends, my invention consists of a novel construction of a package tie and tying cord inseparable therefrom, comprising the novel features of utility and advantage hereinafter set forth.

For the purpose of illustrating my invention, I have shown in the accompanying drawings one form thereof which is at present preferred by me, since the same will give in practice satisfactory and reliable results, although it is to be understood that the various instrumentalities of which my invention consists may be variously arranged and organized and that my invention is not limited to the precise arrangement and organization of these instrumentalities as herein shown and described.

Figure 1 represents a perspective view of a package tie embodying my invention, showing the tying operation completed.

Figure 2 represents a section on line 2—2 60 Figure 1.

Figure 3 represents a plan view of the tie with the tying cord removed.

Figure 4 represents the first step in the operation of tying.

Figure 5 represents the second step in the tying operation, which is shown as being completed in Figure 1.

Similar numerals of reference indicate corresponding parts.

Referring to the drawings:—

In carrying out my invention, I employ a plate or body 1, which may be composed of vulcanized fibre, thin sheet metal or any other suitable material, and which is provided at about its median line with an eye 2 into which leads the converging walls 3 and 4, whereby a tapering throat is formed for the purpose of instantly assembling the cord to the plate without putting the device out of commission for repair, terminating in the opening 5, which is of such dimensions that the cord 6 while freely movable longitudinally in said opening, cannot be pulled laterally through said opening.

6 and 7 designate inclined walls which enter the body of the tie obliquely to the walls 3 and 4, said wall 6 merging into the curved wall 8, which is continued to form the inclined wall 9, which meets the inclined wall 10 at the apex 11, this apex 11 being to one side of the median line of the tie and out of alignment with the eye 2, whereby an oblique slot 15 is formed which terminates in the opening 16.

12 designates a recess or shoulder on the side of the tie body, which is located intermediately of the apex 11 and the eye 2. The tying cord 6 is provided at each end with the heads 13 and 14, which are preferably made of cement or similar material, which is impervious to heat or moisture, and I desire to call special attention to the fact that the dimensions of the cord 6 are such that while it can be pulled through the eye 2, it fits sufficiently snugly in said eye so that it can not be withdrawn laterally therefrom through the opening 5, and that the plate or body 1 and the cord 6 with its cement heads are always a concrete, unitary structure, neither one being capable of separation from the other.

In the application or use of my invention, the body or plate 1 is placed flat on the merchandise to be tied and the end of the cord carrying the head 14 is pulled through the oblique slot 15 into the position seen in Figure 4 and a pull exerted thereon until the head 13 assumes the position seen in Figures 1, 2 and 5. The cord is then pulled tightly and the extremity carrying the head 14 is then switched flat on the plate around into the recess 12 into the second position seen in Figure 5. The free end of the cord is then passed down under the plate up again into the oblique slot 15 and pulled until the parts assume the last or final position seen in Figure 1, in which position the cord will be locked.

To unlock or untie the device, it is only necessary to draw the free end of the cord containing the head 14 down into the oblique slot between the walls 6 and 7 and then exert a pull thereon.

My device is of great utility, since it is capable of re-use to an almost indefinite extent, thereby effecting a great saving in twine or cord, and in addition, when one end becomes worn from the repeated tying operations, the other end can be used, so that the life of the device is redoubled. The heads 13 and 14 are preferably of cement or similar material impervious to heat or moisture, and if desired a knot may be tied in each end before the application of cement thereto.

It will now be apparent that I have devised a novel and useful package tie which embodies the features of advantage enumerated as desirable in the statement of the invention and the above description, and while I have in the present instance, shown and described a preferred embodiment thereof which will give in practice satisfactory and reliable results, it is to be understood that the same is susceptible of modification in various particulars without de-

parting from the spirit or scope of the invention or sacrificing any of its advantages.

Having thus described my invention, what I claim as new and desire to secure by Letters Patent, is:—

1. A package tie, comprising a tie body having an oblique slot entering one edge thereof and terminating near the middle of said body in converging walls, which extend at an angle to said slot and meet at an apex located out of alignment with said slot, and an inclined passage formed by converging side walls merging into said oblique slot and terminating in an eye located on substantially the median line of said body, the diameter of said eye being greater than the width of said passage leading thereto at its terminal, and the edge of said body opposite to said oblique slot having a recess therein located intermediately of said apex and eye, and a cord passing freely through said eye but incapable of disengagement therefrom and having cement heads attached to its ends, whereby said cord is incapable of disengagement from the tie body in a lateral or longitudinal direction and forms a unitary structure therewith. 55 60 65

2. The combination of a tie body having an opening in the side thereof terminating in converging walls merging into an eye of considerably greater area than the constricted throat leading thereto, a tying cord passing through said eye and of such size as to be longitudinally movable therethrough 75 but incapable of lateral disengagement therefrom, and an enlarged cemented knot on each end of said cord, whereby said cord cannot be laterally or longitudinally disengaged from said eye or body and forms a 80 85 unitary structure therewith.

GEORGE W. STOUT.
